[57] CLAIM

The ornamental design for a seat, as shown and described.

DESCRIPTION

FIG. 1 is a front perspective view of a seat according to our new design;

FIG. 2 is a front elevational view of our new design;

FIG. 3 is a side elevational view of the design, the opposite side being a mirror image thereof;

FIG. 4 is a top plan view of the design;

FIG. 5 is a rear elevational view of the design;

FIG. 6 is an enlarged cutaway perspective view of a front corner of the design;

FIG. 7 is a front elevational view of a seat according to a second embodiment of our new design, the difference being primarily a matter of length;

FIG. 8 is a top plan view of the second embodiment of the design; and,

FIG. 9 is a rear elevational view of the second embodiment of the design.

The side view of the second embodiment would be like that shown and described in FIG. 3.
